JOHN DANIAL, OF SYRACUSE, NEW YORK.

CLOCK-CONTROLLED ELECTRIC SWITCH.

Application filed January 20, 1925. Serial No. 3,581.

This invention relates to a clock controlled electric switch for opening and closing a lighting or other electric circuit at regular predetermined intervals.

5 The main object is to provide a simple, compact, switch-operating device as an attachment to an ordinary clock whereby the switch controlling may be set to close and to open the circuit at the beginning and at 10 the end of different intervals of time and to remain in this set position for recurrent operations during each twenty-four hour period. One of the specific objects is to provide a clock with an attachment of this 15 character for closing a lighting circuit at a set time and to break the circuit at another set time within the twenty-four hour period whereby the circuit will be closed during the intervening time, each twenty-four hours 20 without further attention on the part of the user.

Other objects and uses relating to specific parts of the device will be brought out in the following description.

25 In the drawings:

Figure 1 is a face view of an ordinary clock equipped with my circuit controlling attachment.

Figure 2 is an enlarged, vertical sectional view taken on line 2—2, Figure 1.

Figure 3 is a fragmentary sectional view taken in the plane of line 3—3, Figure 2.

Figure 4 is a fragmentary sectional view taken in line 4—4, Figure 2.

35 The clock to which the circuit controlling device is attached may be of any standard construction having the minute hand —m— and hour hand —h— mounted on the customary spindle —s— for rotary movement 40 which is journaled in the case and adapted to be rotated by any suitable spring motor and gear train.

The circuit controlling attachment comprises a rotary and axially movable spindle 45 —1— journaled in the upper portion of the clock case —C— directly over and parallel with the minute spindle —s— and having its rear end projecting beyond the back of the case —C— and provided with a hand wheel 50 —2— by which it may be rotated and moved axially, the forward axial movement being limited by a tube —3— engaging the back of the case.

The front end of the spindle extends 55 through and beyond the dial plate —d— of

the clock and is provided with a pointer —4— movable around supplemental dial —5— on the plate —d—. A spring —6— is interposed between a shoulder —7— on the spindle —1— and the inner face of the back plate of the case —C— for urging the spindle axially until limited by the engagement —3— with the rear face of the same plate for a purpose presently described. A pair of terminals —8— of an electric lighting circuit —9— are secured to the back plate of the case —C— directly above the spindle —1— and in spaced relation to each other and also insulated from the case by any suitable insulating means, said terminals having contact members —10— at the inner side of the case to form a part of the electric switch which controls the lighting circuit. A movable switch member —11— is pivoted at —12— to a switch lever —13— which, in turn, is pivoted at —14— to an upright partition —c— within and forming a part of the case —C—, said switch lever —13— being extended vertically above and below the spindle —1— and is provided with a vertically elongated opening —15— through which the spindle —1— extends thus permitting the free forward and rearward rocking motion of the switch lever relatively to said spindle.

As previously stated the minute spindle —s— is driven by the usual clock train but is utilized for driving a supplemental gear train consisting in this instance of a pinion —16— which is secured to the spindle —s— and meshes with a relatively larger gear —17—, a pinion —18— and relatively large gear —19—.

The gear —17— and pinion —18— are mounted co-axially upon a relatively short shaft —20— which is journaled in suitable bearings in the partition —c— and dial plate —d—.

The gear —19— is loosely mounted upon the spindle —1— between the partition —c— and dial plate and is provided on its front face with an integral cam —21— concentric therewith but of relatively smaller diameter, said gear being also provided with a forwardly extending lug —22— beyond the periphery of the cam —21— for a purpose presently described.

A ratchet gear —23— is provided with a central forwardly projecting hub —24— journaled in a suitable bearing in the dial

plate —d— co-axial with the gear —19— spindle —1— and, therefore, the setting of and between said gear and dial plate and is provided with a substantially semicircular slot —25— for receiving the lug —22—, the 5 rear face of the ratchet wheel being provided with a semicircular rib —26— extending circumferentially from the ends of the slot —25—. A pointer —4'— is secured to the front end of the hub —24— to rotate 10 with the ratchet wheel around the dial —5— which is shown as provided with a series of gradations reading clockwise and numbered in sequence from three to twelve inclusive representing corresponding hours, the 15 twelve number being arranged directly over the axis of the spindle —1—, said gradations being continued from the numeral twelve in sequence from one to six representing hours of the morning or after the mid-night hour twelve.

The hand or pointer —4— is set to represent the beginning of the closing of the electric circuit while the other pointer —4'— is set to represent the time of breaking the circuit. The hub of the pointer —4'— is provided with a forwardly projecting lug —27— adapted to enter a peripheral slot —28— in the hub of the pointer —4'— as shown in Figure 1 for interlocking those two parts together when the spindle —1— is drawn rearwardly and thereby causing the two hands to rotate in unison in a manner hereinafter more fully described. An arm —29— is secured to the spindle —1— between the cam —21— and ratchet wheel —23— to ride upon the adjacent cam face of said cam. A bow spring —30— is interposed between the partition —c— and gear —19— for pressing said gear forwardly and thereby holding the cam —21— against the arm —29—.

The lug —27— and its pointer —4'— are diametrically opposite each other and in like manner the notch or recess —28— and its pointer —4— are diametrically opposite so that when the pointers are alined with each other, the lug —27— and slot —28— will be similarly alined at which time the spindle —1— may be drawn rearwardly to cause the lug —27— to enter the slot —28— for locking the two pointers together so that by turning the spindle —1— counterclockwise by means of its hand piece —2—, the pointer —4'— may be set to the hour, in this instance eleven, of the dial —5— as the time at which the switch member —11— is to be opened after which the spindle may be released to allow its spring —6— to force it forwardly for disengaging the pointer —4— from the pointer —4'— and permitting the spindle to be again turned to the hour, in this instance, five, at which it is desired to close the switch member —11—.

The pointer —4— and arm —29— extend 65 radially in the same direction from the

the hand —4— will cause the arm —29— to be set to a similar position.

A detent —31— on the back of the dial —d— is yieldingly held against the teeth of the ratchet wheel —23— by means of a spring —32— to prevent said ratchet wheel from being turned clockwise while permitting it to be turned counterclockwise as previously stated.

The supplemental gear train of the circuit controlling attachment is arranged so as to cause the gear —19— to make one complete revolution every twenty-four hours or one half revolution in twelve hours, said gear 20 together with its cam —21— and lug —22— being rotated continuously in the direction indicated by arrow —x—, Figures 3 and 4.

The cam —21— is formed upon the end face of an annular flange on the gear —19— to ride against the arm —29— when the latter is set to the desired hour for closing the switch, said cam face consisting of a semicircular raised or high part and a semicircular low part, the end of the high part in the direction of rotation being gradually beveled off to the low part at —21'— while the other end of the high part terminates abruptly at —21''— to the low part and corresponds to the position of the hour hand —h— of the 90 clock and, therefore, makes one-half revolution with each complete revolution of the 95 hour hand —h—.

Now, if the pointer —4— of the supplemental dial —5— is set to any particular hour as, for example, at five, sometime before the hour hand —h— of the clock registers with the same hour on the main dial, the arm —29— will be set a distance ahead of the point —21''— corresponding to the interval 100 between the time of setting and the hour at which the pointer is set so that as the gear wheel —19— and its cam —21— rotates through that interval the abrupt point —21''— of the cam will have just passed 105 the arm —29— and allow the spring —30— to force the gear wheel —19— and its cam —21— together with the lug —22— thereon forwardly and axially to engage the adjacent low part of the cam with the arm 115 —29—.

The spring —30— is secured at its upper end to the partition —c— some distance above the spindle —1— while its lower end extends some distance below the spindle and is curved rearwardly through an opening in the partition —c— to engage the lower end of the switch lever —13— which is spring pressed against the lower end of the spring —30—.

It is, therefore, evident that when the high part of the cam drops off from the arm —29— at the point —21''— and the gear and cam are forced forwardly by the spring —30— the lower end of the spring will be 120 125 130

sprung forwardly thereby releasing the lever —13— and permitting its contact member —11— to be pressed against the terminals —10— to close the circuit —9—.

5 As previously stated, the slot —25— in the ratchet wheel —23— is substantially semi-circular and its diametrically opposite ends lie in substantially the same radial direction as the pointer —4— so that when the said 10 pointer is registered with any particular hour as, for example, eleven, on the supplemental dial —5— the hands of the slot —25— will have a similar position to allow the lug —22— on the gear —19— to enter the 15 slot and thus permit free forward movement of the gear and cam by the spring —30— in the manner previously described.

This arrangement permits the lug —22— to travel in the slot —25— through a maximum 20 period of twelve hours but owing to the fact that the pointer —4— has been set some time, in this instance, one hour and one-half ahead of the point —21— the lug —22— must move through a corresponding interval 25 lengthwise of the slot —25— before the arm —29— drops off from the abrupt point —21— on to the low part of the cam —21— to close the switch at which time the lug —22— would enter the slot —25— substantially 30 midway between its ends or, in this instance, six hours ahead of the time of closing as indicated by the pointer —4— or eleven o'clock.

At that hour the lug —22— will have 35 reached the upper end of the slot —25— and will then ride upon the rib —26— thereby forcing the gear wheel —19— rearwardly and causing a corresponding movement of the free end of the spring —30— and adjacent end of the switch lever —13— to disengage the switch member —11— from the terminals —10— for breaking the circuit.

It will be observed that the pointers —4— and —4'— have been set to keep the circuit 40 closed for a period of six hours or between the hours five o'clock p. m. and eleven o'clock p. m. during which time substantially one-half of the low part of the cam —21— will 45 be registered with the arm —29— and at the end of that six hours the lug —22— will reach the upper end of the slot —25— and ride upon the rib —26— to cause the opening of the switch and inasmuch as the rib is 50 semicircular and the gear —19— rotates one-half revolution in twelve hours it is evident that the rib cooperating with the lug —22— will hold the switch open during the next 55 twelve hours at which time the high part of the cam —21— will have been again brought into registration with the arm —29— to hold the gear —19— against forward movement and consequently holding the switch open until the abrupt shoulder —21'— is again registered the arm —29— 60 as previously explained, following which the

operation described will be repeated and this repetition will occur during every twelve hours.

It is evident however that the pointers —4— and —4'— may be set to other hours 70 other than those indicated with similar results of closing and opening the lighting circuit.

What I claim is:

1. In a clock controlled electric switch, a 75 dial having hour graduations, pointers movable independently of each other around the dial to register with different graduations, one of said pointers being movable axially and provided with means for engaging and rotating the other pointer when moved axially in one direction for setting said other pointer to register with one hour graduation, said axially movable pointer being freed from interlocking engagement 85 with the other pointer when moved axially in the opposite direction to enable it to be set to another hour graduation of the dial, a bearing member movable rotarily with the axially movable pointer, an axially movable 90 clock rotated cam having a high part and a low part successively registerable with the bearing member and spring-pressed axially into engagement therewith, a self-closing switch member, and means actuated by the 95 axial movement of the cam in one direction for opening the switch member when the high part of the cam is registered with the bearing member and for permitting the closing of the switch member when the low 100 part of the cam is registered with the bearing member.

2. In a clock controlled electric switch a dial having hour graduations, pointers movable independently of each other around the 105 dial to register with different graduations, one of said pointers being movable axially and provided with means for engaging and rotating the other "pointer" when moved axially in one direction for setting said other pointer to register with one hour graduations, said axial movable pointer being freed 110 from interlocking engagement with the other pointer when moved axially in the opposite direction to enable it to be set to another hour graduation of the dial, a bearing member movable rotarily with the axially movable pointer, an axially movable 115 clock rotated cam having a high part and a low part successively registerable with the bearing member and spring-pressed axially into engagement therewith, a self-closing switch member, means actuated by the axial movement of the cam in one direction for opening the switch member when the high part of the cam is registered with the bearing member and for permitting the closing of the switch member when the low part of the cam is registered with the bearing member; and additional clock-controlled means 120 125 130

- for moving the cam member axially against the action of the spring to open the switch while the portion of the low part of the cam is registered with the bearing member.
- 5 3. In a clock controlled electric switch, a dial having hour graduations, pointers adjustable at will to register with different graduations on the dial, when one of said pointers being movable axially and provided
10 with means for interlocking engagement with the other pointer for setting the second named pointer to any one of the graduations when moved axially in one direction and for disengaging said second pointer when moved
15 axially in an opposite direction for permitting the first named pointer to be registered with another graduation, a bearing member rotatable with the second named pointer, a clock rotated gear having separate cams for engaging said bearing members respectively, 30 one of the cams being provided with a high part and a low part, a spring for pressing the gear axially to cause the cams to engage their respective bearing members, means actuated by the axial movement of the gear 35 when the high part of one of the cams is engaged with its bearing member for opening the switch, said means being released when the low part of said cam is registered with its bearing member to permit the switch to close, the other cam engaging its cam member only when the low part of the first named cam member is registered with its bearing member for opening the switch.

In witness whereof I have hereunto set my hand this 7th day of December 1924.

JOHN DANIAL
